UNITED STATES PATENT OFFICE.

IRA A. McCORMACK, OF RIDGEFIELD PARK, NEW JERSEY, ASSIGNOR TO THE MILLER LOCK COMPANY, OF PHILADELPHIA, PENNSYLVANIA, A CORPORATION OF PENNSYLVANIA.

DESIGN FOR A PADLOCK.

Application filed February 6, 1922. Serial No. 557. Term of patent 14 years.

To all whom it may concern:

Be it known that I, IRA A. McCORMACK, a citizen of the United States, residing in Ridgefield Park, Bergen County, New Jersey, have invented a new, original, and ornamental Design for a Padlock, of which the following is a specification, reference being had to the accompanying drawing, forming part thereof, in which:—

Fig. 1 is a face view of the padlock showing my new design; and

Fig. 2 is an edge view of the padlock I claim:

The ornamental design for a padlock, substantially as shown.

IRA A. McCORMACK.
